ABSTRACT

A wood chip cutting machine comprises a casing with a drum shaped cutter cage therein, the cage having a plurality of inwardly pointing cutters spaced around it. Cooperating with the cage is a rotor having arms each of which carries a thin double-edged blade. Each blade is replaceable, and is clamped on its rotor arm by a retaining strip held in place by bolts. The blade protrusion is only about equal to the blade thickness, which is preferably 2 mm.

WOOD CHIP CUTTING MACHINE

The invention relates to a rotary chip cutting machine for producing wood chips, having chip cutter blades which cooperate with cutters forming a cutter cage.

BACKGROUND OF THE INVENTION

In chip cutting machines the blades are subjected to extreme wear and tear. To obtain a satisfactory cut and a favourable service life of the cutting edges of the blades, these are made of high quality and hence costly material, and are secured interchangeably to a base by means of countersunk screws. The blades are made relatively thick to enable such screw fastening to be effective. The disadvantage of this prior art embodiment is that because of the quantity of high quality material used, the production of a rotor for a rotary chip cutting machine is costly.

A further disadvantage is that since the cutting edges become blunt due to excess wear, the chipping quality diminishes over a period of time.

It is an object of the invention to provide an improved rotary chip cutting machine, more especially the chipping blades of which are of simple structure require only a small quantity of high quality material, and substantially ensure the production of chips of uniform size. Moreover the cutting blades of this invention have a long service life, are positioned reliably and are easily interchanged.

According to the present invention there is provided a chip cutting machine for producing wood chips including a drum-shaped cutter cage fixed in a housing and provided on its circumference with cutter ribs in spaced relationship to one another, a plurality of cutters secured thereto by fixing means, a chip cutting rotor rotating in said cutter cage and connected to a driving device, said rotor being provided with rotor arms having chip cutting blades co-operating with the cutters of the cutter cage, each blade being clamped between a supporting surface of a rotor arm and a detachable fixing strip by securing means therefor, said blades being of a thickness between 1 and 5 mm, and having two cutting edges so as to be reversible.

In a preferred embodiment each chipping cutter is formed as a thin cutter blade having a thickness of between 1 and 5 mm, preferably 2 mm, and is provided with opposing cutting edges; when one cutting edge has worn out, the blade can be turned through 180° to use the second cutting edge.

This thin cutter is a cheap discardable item and can be made with or without any cutting edge armour; the embodiment without armour and hence the cheapest is preferred.

The individual cutters are clamped with the exception of a cutting edge projection corresponding to the cutter thickness, between a rotor arm and a retaining ledge. The retaining ledge, cutter and rotor arm are secured by fixing screws passed therethrough. The fixing screws can be formed with surfaces acting directly on the blades.

At a cross-sectional corner remote from the cutter a retaining ledge is chamfered and/or radiused, so that when a cutter is located within the cutter cage, a receiving space is formed between the retaining ledge and cutter cage to reduce the cut material to small pieces.

To enable a chipping cutter with a worn cutting edge to be turned, each cutter has a retaining strip with its longitudinal edges recessed, with a cutter projection opposite the cutting edge, so that only the nuts of the fixing bolts need be removed, the assembly unit (cutter, retaining strip and fixing bolts) being drawn off the rotor arm, turned through 180°, and fixed anew to the rotor arm.

Since each cutter is relatively thin, the construction in accordance with the invention uses only a small quantity of high quality material and is thus extremely economical.

On account of their projection beyond the holder to a distance corresponding to the cutter thickness, the individual blades can wear only up to the holder and then can be reversed or interchanged in good time, so that the deterioration of chip quality occurring in hitherto known designs due to excessive cutting edge wear are substantially eliminated.

The invention will be described further, by way of example, with reference to the accompanying drawings, in which:

FIG. 1 is a perpendicular longitudinal section through a rotary chip cutting machine having a cutter cage fixed in a casing, and a chip cutting rotor cooperating with it;

FIG. 2 is a cross-section through the cutting means of chip cutting rotor and the cutter cage surrounding it;

FIG. 3 is a cross-section on an enlarged scale through the cutting means of the chip cutting rotor;

FIG. 4 is a front elevation of a chip cutter as used on the rotor, showing the retaining ledges in chain dotted lines; and

FIG. 5 is a schematic drawing showing the relative orientation of the blades.

A chip cutting machine in accordance with the invention for producing wood chips has a housing 25 in which a drum-shaped cutter cage 10 is mounted; this cutter cage 10 is provided on its circumference with spaced fixing ribs 26, to which two cutters are detachably mounted with cutting edges facing in opposite directions (located at an angle to one another), i.e. cutting blade 14 and a stock blade 15 are detachably mounted. The stock blade 15 is retained interchangeably by fastening bolts 27, and the cutting blade 14 by a retaining strip 28 held against the cutting blade 14, and secured by bolts 29 to the cutter cage rib 26. An adjustable chip passage gap 30 is formed between the leading cutting blade 14 in the direction of rotation of the rotor, and the adjacent cutter cage rib 26 holding the rear stock cutter 15 through which gap the chips produced arrive in the chip space 32.

A chip cutting rotor 11 mounted rotatably in the housing 25 extends within the cutter cage 10 and is provided with rotor arms 11 forming beating vanes, each carrying chip cutting blades 13 having cutting edges 13a, 13b; each blade is detachably mounted on each rotor arm 12 and co-operates with the cutters 14, 15 of the cutter cage 10. The chip cutting rotor 13 is driven by a shaft 31 which is either directly connected to a driving device (not shown) such as a motor, or indirectly via gear means such as a belt pulley and belt.

The housing 25 forms a chip space around the cutter cage 10 from which space there is at least one chip removing opening on the underside.

The housing 25 is closed at the end face opposite the driving side, by a cover 34 mounted detachably on the

housing 25, through which opening the cutter cage 10 can be removed from the housing 25 for replacing its cutters 14, 15.

The cutter cage 10 is of frusto-conical shape tapering towards the cover 34, and the rotor is also frusto-conical. The rotor driving shaft 13 is substantially horizontal.

The cutter cage ribs 26 are provided with a coating 35 such as an impact-resistant armoured coating at their inside surface between the two cutters 14, 15, facing the rotor 12. The housing 25 in the upper region opposite the cover 34 has a timber inserting opening 36.

Each blade 13 co-operating with the cutting blades 14 and the stock blades 15 is supported against the wall of its rotor arm 12 leading in the direction of rotation of the chip cutting rotor, by means of centering bolts or centering projections, and is fixed laterally and vertically and clamped by means of a retaining strip 16 detachably mounted on the rotor arm 12.

Each blade 13 is located with its cutting edge within the rotational jacket of the rotor 11 and thus extends diagonally to the rotational axis of the rotor 11; this cutter position is established by rotor arms 12 extending diagonally to the axis of rotation of the rotor.

The rotor arm 12 for the blade mounting, provided with an impact resistant armour coating 17 on its end, has a space 18 located in the frontal corner region in the direction of rotation, and also a plurality of bores 19, passing through the wall thickness.

For mounting purposes each blade 13 has at least one retaining strip 16 associated therewith which is at least partly accommodated in the space 18 and by means of which it is detachably secured by fixing screws 20 passing through the blade 13 and rotor arm 12, with nuts 21 screwed on the free ends thereof.

Each blade 13 is provided with fixing holes 22 for its positional location. These fixing holes 22 register with screw holes 23 in the retaining strips 16, so that the same fasteners are used for the retaining strip 16, exerting a clamping action, against the blade 13.

For centering the blades 13 the fixing screws 20 are provided at the head end with a cylindrical portion 20a, which are a close fit in the blade fixing holes 22.

The blade 13 is between 1 and 5 mm thick, preferably 2 mm, and has two opposed cutting edges 13a, 13b so that it is reversible. The blade 13 has a uniform cross-section over most of its length, but tapers towards its two end faces.

The retaining strips 16 have a shape similar to the shape of the blades, but are slightly smaller, so that in the region of at least one lateral edge of the cutter blade projects. The retaining strip 16 is preferably set back at both sides relative to the cutting edges 13a, 13b of the blade 13 (see FIG. 4) so that it is easy to reverse the blade 13.

The retaining strip 16 receives the screw heads of the fixing screws 20 in a recess. At least one corner of the retaining ledge cross-section remote from the cutting edge of the blades is chamfered and/or radiused, so that a space 24 is formed in front of the chip cutting edge 13a or 13b to receive the small pieces of wood cut off by the blades. The retaining strip cross-section may be trapezoidal or have the shape of a section of a circle.

The chip cutting rotor 11 may be made as a frusto-conical or cylindrical rotor. Its rotor arms 12 may be provided in the longitudinal extension of the rotor, or have an inclined position.

The blade is usually made without cutting edge armour; it may, however, be provided with such an armour.

The blade 13 in accordance with the invention is made of a high quality material of low weight and can be discarded after having using and wearing both its cutting edges 13a, 13b successively. Replacement of the blade 13 is easy to carry out. Since there is only a relatively small length of blade projecting relative to the chip cutting blade holder, the cutting blade 13 can wear only to a slight extent corresponding to the blade thickness, which in comparison with known embodiments leads to early replacement of the cutting edges. This avoids the considerable differences in chip size produced in older machines by cutter wear.

I claim:

1. A chip cutting machine for producing wood chips, including a housing, a drum-shaped cutter cage fixed in said housing, cutter ribs in spaced relationship provided around the circumference of said cage, a plurality of cutters secured to said ribs, a chip cutting rotor rotating in said cutter cage, a driving device for said rotor, rotor arms on said rotor, chip cutting blades on said rotor arms co-operating with said cutters of said cutter cage, and a detachable fixing strip clamping each blade to a supporting surface on each rotor arm, said blades being of a thickness between 1 and 5 mm, and having two cutting edges so as to be reversible.

2. A chip cutting machine as recited in claim 1, wherein said ribs extend diagonally to the axis of rotation of said rotor, said chip cutting blades tapering towards the ends with their cutting edges located within the drum shaped cutter cage and being interchangeably mounted on said ribs, said blades being located on the generating line of a conical frustum and coacting with the cutters of said cutter cage which is also frusto-conical, each said cutter comprising a cutting blade leading in the direction of rotation of said rotor and a rear stock blade in the direction of rotation of said rotor, said cutters being mounted detachably at an angle relative to one another by means of screws on said ribs to define an adjustable chip passage gap leading towards a chip space defined between a stock blade and a cutting blade.

3. A chip cutting machine as recited in claim 1, wherein said blades have their cutting edges located on the generating line of a cylinder and are adapted to co-operate with the cutters of a cylinder cutter cage, said cutters comprising a cutting blade leading in the direction of rotation of said rotor and a rear stock blade in the direction of said rotor, said cutters being detachably mounted at an angle relative to one another to define an adjustable chip passage gap leading towards a chip space defined between a stock blade and a cutting blade.

4. A chip cutting machine as recited in claim 1, in which each cutting blade is locationally fixed by screws and a retaining strip, and is clamped in a receiving space defined by said rotor arm, with only a length of blade equal to the blade thickness protruding.

5. A chip cutting machine as recited in claim 4, wherein said cutting blades taper towards their ends and said retaining strips are similar in basic shape to said cutting blades, but smaller in width to leave a portion of blade unclamped.

6. A chip cutting machine as recited in claim 4, wherein said retaining strips are reversible and are bevel-

elled at both longitudinal edges relative to the cutting edges of the associated blade, and radiused along one lateral longitudinal edge, each strip defining recesses for the heads of said fixing screws.

7. A chip cutting machine as recited in claim 1, comprising a plurality of fixing screws for each retaining

strip, each cutting blade and each of said rotary arms, each screw having a partially cylindrical guide shaft passing through said strip and blade, and a nut on each bolt on the side of said rotor arm rearwards with respect to the direction of rotation of said rotor.
